UNITED STATES PATENT OFFICE.

ROBERT STANTON AVERY, OF WASHINGTON, DISTRICT OF COLUMBIA.

DESIGN FOR A FONT OF PRINTING-TYPE.

SPECIFICATION forming part of Design No. 22,478, dated May 30, 1893.

Application filed April 28, 1893. Serial No. 472,271. Term of patent 14 years.

To all whom it may concern:

Be it known that I, ROBERT STANTON AVERY, a citizen of the United States, residing at Washington city, in the District of Columbia, have invented and produced a new and original Design for a Font of Printing-Type, of which the following is a specification, reference being had to the accompanying drawing, showing a part thereof.

10 My design is for a font of phonetic printing type, which is fully illustrated in the accompanying drawing, the same showing both upper and lower case letters and numerals.

15 The consonants are shown in the first four lines, the vowels in the next four lines, and numerals in the next or last line.

20 The whole number of letters in my new phonetic alphabet is forty-two, and each has a definite and distinctive phonetic value in carrying out a system which I have devised

and practically applied in printing and otherwise.

It is unnecessary, for the purposes of a patent grant, to give here the phonetic value or equivalents of the several letters, by means 25 of letters or combinations of letters forming the ordinary English alphabet in common use. Nor is it necessary to give the names by which the several letters of my alphabet are distinguished; nor to particularize regarding the peculiarities of form of the letters and numerals themselves, since they are sufficiently apparent upon inspection.

What I claim is—

25 The design for a font of phonetic printing type, substantially as shown.

ROBERT STANTON AVERY.
